(57) **CLAIM**

I claim, the ornamental design for a radiator grille for an automobile, as shown and described.

DESCRIPTION

FIG. 1 is a perspective view of a radiator grille for an automobile showing my present design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view, and,

FIG. 8 is a cross-sectional view thereof taken along line 8—8 of FIG. 2.

The broken lines in FIGS. 3 and 7 show part of the structure that forms no part of the claim.
